UNITED STATES PATENT OFFICE.

CHARLES H. MACDONALD, OF MONTCLAIR, AND LEROY L. SALFISBERG, OF NEWARK, NEW JERSEY, ASSIGNORS TO IVERS-LEE COMPANY, OF NEWARK, NEW JERSEY, A CORPORATION OF DELAWARE.

COATING DEVICE.

Application filed July 8, 1920. Serial No. 394,717.

To all whom it may concern:

Be it known that we, CHARLES H. MACDONALD, a subject of the Kingdom of Great Britain, and a resident of Montclair, county 5 of Essex, and State of New Jersey, and LEROY L. SALFISBERG, a citizen of the United States, and a resident of Newark, county of Essex, and State of New Jersey, have invented an Improvement in Coating Devices, 10 of which the following is a specification.

The present invention relates to an improvement in coating devices which may be used to advantage in connection with packaging machines of the type adapted to 15 close candies, medicinal tablets and the like in a continuous strip of paper to form a protective covering. One object of the invention is to provide a device of the kind described by means of which the package 20 with articles enclosed may receive a coating of paraffin or other suitable material, not only to render the package more impervious to moisture but also to provide adhesive means by which the adjacent folds of such 25 a package may be securely held in contact to form a package of substantially bloc form if desired.

One embodiment of our invention is illustrated in the drawings accompanying the 30 present specification, and in which—

Figure 1 is a front elevation partly in vertical section and with portions broken away,

Figure 2, a detail view of a portion of the 35 flow regulating means,

Figure 3, a fragment of a bloc package such as may conveniently be coated and held together by the improved apparatus,

Figure 4, a vertical section on the line 40 4—4 of Figure 1, and

Figure 5, a detail sectional view of a preferred form of spraying nozzle showing the relative position of the same with respect to the article guiding means.

Referring to the drawings, a supply of 45 coating material such as paraffin is held in a container 1, preferably of metal exposed at the bottom and insulated on the sides by insulating material 2. Heat may be transmitted to the exposed bottom of the metallic 50 container from a resistance element 3 (Figure 4). To control the temperature of the melted paraffin in the container, we provide

a thermostat 4 in effective communication with the container and the melted wax there- 55 in, said thermostat being operatively connected with the resistance element 3 in a well known manner to control the flow of current through said element.

Referring to Figure 1, the article such as 60 a package of candies or medicinal tablets enclosed in a package of strip form and bent or folded transversely in zigzag fashion is guided and supported by a guiding member 5 shown in the drawings as consisting of 65 four substantially parallel rods spaced apart to permit the passage of the article as it comes from the packaging machine (not shown). These rods are preferably bent in such a manner as to alter the direction of the 70 path of the article, thus interposing a slight resistance to its passage so that succeeding folds or layers of the package will be pressed into contact with the preceding layers as the article progresses through the coating operation and after receiving an initial coating of the coating material. As indicated more clearly in Figure 5, the coating material is projected against the article through 75 perforations 6 in opposed nozzles 7, one arranged at each side of the support 5. Thus, the package may be subjected to substantially converging streams of melted paraffin. The coating material is forced into the nozzle 7 through a suitable conduit by means of 80 a pump 8, indicated in Figure 4, the paraffin being drawn into and through said pump from a point adjacent to the bottom of the container. A valve 9 is located at a convenient place in the conduit and is adapted 85 to permit control of the amount of paraffin or coating material supplied to the nozzle 7 by means of a valve operating handle 20 having an adjustable set screw 21 cooperat- 90 ing with a fixed stop 22. The extent of valve opening deflection of the handle 20 is limited by said set screw and stop and, when the flow of paraffin is once determined for a given package, it can be maintained in repeated operations even though the valve may be entirely closed from time to time. This regulation of the valve opening permits the use of a continuously operating pump of 95 constant capacity.

It is contemplated that under some conditions of operation, there will be an excess

of coating material over what is required to effectively coat the surfaces of the package and retain the adjacent portions thereof in adhering contact after the coating material has congealed. To eliminate this excess of material, we have provided a compressed air discharging nozzle 10 arranged to direct a blast of air against the coated article before the coating material has congealed.

10. Perforations 11 in said nozzle direct a blast downwardly while perforations 12 direct a blast transversely. Such excess material as is removed by the air blast finds its way again into the interior of the container. Air 15 under pressure may be supplied to the air blast nozzle through a suitable conduit 13 operatively connected with a compressor 14 or other suitable air compressing element.

As the coated package moves in a direction of the arrow indicated in Figure 1, it is discharged upon a platform 15 arranged at the discharge end of the guiding member 5.

From the foregoing description of the operation of our improved coating device, it will be clear that the coating method therein disclosed includes the step of exposing the article to sprays of paraffin or other suitable coating material and then subjects the 30 coated article to a blast of air to remove the excess coating material, during which time the folds of the article are pressed into contact so that, when the paraffin coating material congeals, the resulting 35 package will be one of substantially bloc form.

We claim as our invention:

1. A coating device for a strip bent transversely to form portions arranged in zigzag relation, comprising a container for coating material, means for applying said material to opposed faces of said portions, and means for yieldingly resisting advance of the coated bent strip to effect adhering contact between said opposed coated faces of portions thereof.

2. A coating device for a strip bent transversely to form portions arranged in zigzag relation, comprising a container for

coating material, means for applying an excess of said material to opposed faces of said portions, means for yieldingly resisting advance of the coated bent strip to effect contact between said opposed coated faces of portions thereof, and means for removing 55 excess coating material from portions held in contact by operation of the advance resisting means.

3. A coating device for a strip bent transversely to form portions arranged in zigzag relation, comprising a container for coating material, means for applying said material to opposed faces of said portions, means for yieldingly resisting advance of the coated bent strip to effect adhering contact between said opposed coated faces of portions thereof, and means for directing a blast of air against said coated bent strip.

4. A coating device for a strip bent transversely to form portions arranged in zigzag relation, comprising the container 1 for coating material, the opposed nozzles 7 for applying said material to the strip, and the strip guide and advance resisting member 5.

5. The method of making a package in bloc form from a continuous strip bent transversely to form portions arranged in zigzag relation which includes applying liquid coating material to opposed faces of said portions, and pressing the coated opposed faces into contact while the coating material is congealing.

6. A coating device for a strip bent transversely to form portions arranged in zigzag relation comprising a container for coating material, means for applying said material, to opposed faces of said portions and means for yieldingly resisting advance of the coated bent strip including edge contacting members bent to form a guideway 60 having communicating portions with their axes disposed at an angle to each other.

In testimony whereof, we have signed our names to this specification this 25th day of June, 1920.

CHARLES H. MACDONALD.
LEROY L. Salfisberg.
